FLUSH TANK BALL VALVE

Charles H. Rennels, 509 Laird Ave., Poland, Ohio

Filed May 24, 1963, Ser. No. 75,058

Term of patent 14 years

(Cl. D91—1)

The figure is a top perspective view of a flush tank ball valve, showing my new design.

The side opposite that shown in the figure is substantially the same.

The dominant features of my design reside in the portions shown in full lines.

I claim:

The ornamental design for a flush tank ball valve, as shown and described.
